UNITED STATES PATENT OFFICE

2,453,200

DOUBLE SEAMER

Edward V. Crane and Karl Kuhn, Brooklyn, N. Y.,
 assignors to E. W. Bliss Company, Brooklyn,
 N. Y., a corporation of Delaware

Application December 10, 1943, Serial No. 513,710

2 Claims. (Cl. 113—24)

1

This invention relates, as indicated, to double seamers, that is to say, machines for double seaming ends to can bodies.

A primary object of the invention is to provide a machine of the character described in which the number of revolving parts which must be started and stopped incidental to each cycle of operation of the machine is reduced to a minimum. Stated somewhat differently, the revolving mass which must be arrested as each can is seamed is reduced as far as possible. To accomplish this, the seaming parts are in constant motion, permitting the seaming head to function in a manner analogous to that of a flywheel, thereby relieving the load on the motor and the clutch, the clutch being called upon only to operate in connecting the intermediate drive of the seaming mechanism for each can to be operated upon.

Another object of the invention is to provide in a machine of the character described an increased rigidity, due to the provision of tubular seaming arms which afford suitable bearing and pivoting of seaming roll levers within the arms and a toggle action which is utilized to apply a seaming pressure.

A further object of the invention is the provision in a machine of the character described of an enclosed master cycle shaft for rotating the seaming head as well as means for reducing the cam load by reason of pair balancing.

A still further object of the invention is to provide in a machine of the character described, a vertical shaft motor which drives the main shaft of the machine by means of a single belt reach, instead of by the conventional twisted belt drive.

A still further object of the invention is to provide a double seamer which is of a neat, attractive design.

To the accomplishment of the foregoing and related ends, said invention, then, consists of the means hereinafter fully described and particularly pointed out in the claims; the annexed drawings and the following description setting forth in detail certain mechanism embodying the invention, such disclosed means constituting, however, but one of various means in which the principle of the invention may be used.

In said annexed drawings:

Fig. 1 is a front elevation of the double seamer selected to illustrate an embodiment of our invention;

Fig. 2 is a top plan view of the double seamer;

Fig. 3 is a side elevation of the double seamer;

Fig. 4 is an enlarged top plan view of the

2

double seamer, with a portion removed to more clearly expose some of the operating mechanism;

Fig. 5 is a view, partly in section, and partly in elevation, taken approximately on the line 5—5 of Fig. 4;

Fig. 6 is a cross-sectional view, taken approximately on the line 6—6 of Fig. 4;

Fig. 6A is a cross-sectional view, on an enlarged scale, of a portion of Fig. 6;

Fig. 6B is a cross-sectional view, through a portion of the seaming head, taken at right angles to the view in Fig. 6A;

Fig. 6C is a perspective view, showing linkage employed in actuating the seaming rolls;

Fig. 7 is a cross-sectional view, taken approximately on the line 7—7 of Fig. 4;

Fig. 8 is a view, partly in plan, and partly in section, taken approximately on the line 8—8 of Fig. 3;

Fig. 9 is a cross-sectional view, taken approximately on the line 9—9 of Fig. 8;

Fig. 10 is a plan view, illustrating in a more or less diagrammatic manner, the location of the seaming rolls and other elements carried by the

seaming head;

Fig. 11 is a plan view of the seamer cam;

Fig. 12 is a transverse cross-sectional view of the seamer cam, taken on the line 12—12 of Fig. 11;

Fig. 13 is a view illustrating the development of the seamer cam;

Fig. 14 is a view, illustrating the timing of the various operations of the seamer;

Fig. 15 is a view showing the profile of one of the first operation rolls of the seamer;

Fig. 16 is a view showing the profile of one of the second operation rolls of the seamer;

Fig. 17 is a view illustrating the first step in the operation of double seaming a can end to a can body;

Fig. 18 is a view illustrating the second step in the operation of double seaming a can end to a can body;

Fig. 19 is a view illustrating the third step in the operation of double seaming a can end to a can body;

Fig. 20 is a view illustrating the retracted position of the seaming rolls after the double seaming operation is completed;

Fig. 21 is a view of a chuck such as used for double seaming round cans;

Fig. 22 is a view, illustrating diagrammatically the location of the various cams of the double seamer relatively to each other;

Fig. 23 is a plan view of the seaming head

which is used in double seaming larger cans of all shapes.

Fig. 24 is a view, partly in elevation, and partly in section, taken approximately on the line 24—24 of Fig. 23;

Fig. 25 is a fragmentary view, illustrating the set-up of certain parts in Fig. 24, when double seaming an oblong or rectangular can;

Fig. 26 is a plan view of an adjustment for one of the levers for increasing the roll travel for wide end flanges, etc., and

Fig. 27 is a side elevation of the parts shown in Fig. 26.

Referring more particularly to Figs. 1 to 22 inclusive, of the drawings, which show the seamer as set up for double seaming round cans, the seamer is seen to comprise a pedestal 1 having a base portion 2 and a pad 3 at its upper end, which provides a support for a housing 4, within which the seaming head and other mechanism to be described are enclosed.

The housing 4 is open at the front, and this opening is adapted to be closed by means of a cover 5, which is hingedly secured, as at 6, to the housing. Mounted on the housing 4 is a top housing 7, for the intermediate drive of the seamer, which will be presently described.

Rigidly secured to the upper wall of the housing 4, is a seaming head support 8 (Fig. 6) about which an annular head gear 9 is adapted to be rotated. The gear 9 has a hub 10 to which a seaming head 11 is keyed.

The support 8 has a lower portion 12 of reduced diameter, and to which is secured, as by bolts 13, a bearing plate 14. The bearing plate 14 by its outer edge portion engages a second bearing plate 15 having a flange 16 which forms a support for the seaming head 11, the seaming head being thus confined against vertical movement by the gear 9 and the plate 15.

To facilitate rotation of the seaming head, a roller thrust bearing 17 is interposed between the bearing plates 14 and 15.

The seaming head 11 is provided with four radially extending hollow arms 18, which are spaced circumferentially 90 degrees apart, each arm having a vertical bore 19, within which is disposed the upright hub 20 of a tubular seaming arm 21, the hub 20 being locked to the arm 18 by means of a collar 20a. The seaming arm has pivotally connected thereto, as at 22, a seaming roll lever 23 having a depending portion 24 upon which is journaled a seaming roll 25.

The lever 23 is adapted to be rocked in a horizontal plane about its pivotal axis 22, and for this purpose it has connected thereto, as at 26, a connecting link 27 which extends through the arm 21 and is connected at its outer end to an adjustably mounted bell crank 28. The crank 28 is mounted on the arm 21, as at 29, for rocking movement in a vertical plane. Extending through a hole 30 in the crank 28, and in threaded engagement therewith, is an adjusting screw 31 having a knurled knob 32 secured to its outer end, and provided at its inner end with a cup 22 which bears against the ball head 34 of a stem 35.

The stem 35 is slidably mounted in a fork 36, which is disposed within the hub 20 of the seaming arm, and is vertically reciprocable in the latter, the stem being secured against displacement from the fork by a nut 37 secured to the upper end of the stem. A preloaded coil spring 38 is mounted on the stem 35, being interposed

between the fork 36 and a washer 39 resting on the head 34 of the stem.

It will be apparent from the foregoing description that downward movement of the fork 36 will be communicated through the spring 38, stem 35, screw 31, crank 28, and link 27 to the lever 23, so as to rock the lever and move the seaming roll 25 thereof to an operative position. Adjustment of this movement may be effected by adjustment of the screw 31, which changes the effective point of connection of the stem 35 to the crank 28. The spring 38 is effective to absorb shocks occasioned by irregularities encountered during the seaming action of the roll 25.

For the purpose of effecting a return of the roll 25 to its retracted or inoperative position, a tension spring 40 is provided, which is connected at one end to the arm 21, and at its other end to a groove pin 41, which extends from the lever 23. A stop or plug 41a, which is interposed between the screw 20a and the fork 36 operates to limit the return movement of the roll.

Threadedly secured to the lower bearing plate 14 is a pin 42 having an axial bore 43 extending therethrough which is in alignment with an axial bore 44 in the support 8. The threaded pin 42 has a portion which projects through the lower face of the plate 14 and has secured thereto a chuck 45 having an axial bore 46 (Fig. 21) in alignment with the bores 43 and 44. Secured to the lower end of this chuck is chuck plate 47 against the lower face of which the end of the can which is to be double-seamed is clamped by means which will be presently described.

The seaming rollers 25 are adapted to be simultaneously moved into operative engagement with the work to be double-seamed, and for this purpose, mechanism is employed, which will now be described.

Such mechanism comprises a spider 48, which is mounted upon a bearing 49 which, in turn, is mounted on the support 8, the spider being retained against endwise displacement from the bearing 49 by means of a lock nut 51, which is threadedly secured to the lower end of the bearing. The spider is provided with radially-extending ears arranged in pairs, the ears in each pair being diametrically-opposed to each other. One pair of these ears, designated 52, is shown in Figs. 6 and 6A, and the other pair, spaced 90 degrees from the ears 52 circumferentially of the spider, and designated 52a, is shown in Fig. 6B. The ears 52 have journaled therein pins 53 having flat portions 53a, to which are secured toggle links 55, arranged in pairs, each pair of toggle links being secured at its outer ends to a pin 56, which is mounted in a bell-crank 57. The ears 52a have journaled therein pins 53' having flat portions 53b, to which are secured toggle links 55a, arranged in pairs, each pair of such links being secured at its outer ends to a pin 56, which is mounted in the ears 52a at a somewhat higher elevation than the pins are mounted in the ears 52. Moreover, the links 55a are somewhat longer than the links 55, that is to say, the distances between the axes of the pins 53' and the pins 56 to which the links 55a are connected, are greater than the distances from the pins 53 and the pins 56 to which the links 55 are connected. The linkage embodying the links 55a operates the first operation rolls, as hereinafter described, while the linkage embodying the links 55 operates the second operation or finishing rolls.

Each bell crank 57 is pivotally connected, as by

shaft 58, to an arm 18 of the seaming head 11, and the outer arm of each bell crank is connected, as by pins 59, to one of the ball stem forks 36, which have been previously referred to. The walls of the cylindrical hub portions 20 of the seaming arms 21 are slotted to allow the rocking movement of the bell cranks 57, when vertical movement is imparted to the spider 48 in order to rock the rollers 25 to their operative position.

This vertical movement of the spider 48 is effected in the following manner: Secured to the upper flange of the bearing 49 are four push rods 58a, which are spaced apart 90 degrees circumferentially of the bearing and extend upwardly through openings 59a in the support 8, the push rods having a slide fit in the support so as to be freely movable up and down in the support. These push rods also extend through the upper wall of the housing 4, and are provided at their upper ends with threaded stems 60, whereby the push rods are connected, as by means of nuts 61 to a yoke 62.

Yoke 62 is pivotally connected to links 63, which are pivoted at their upper ends to the inwardly extending arm 64 of a rocker lever 65. Lever 65 is pivotally supported, as at 66, on a support 67, which is rigidly secured to the upper wall of the housing 4. The other arm 68 of the lever 65 is pivotally connected to a pair of links 69, the opposite ends of which are connected to a slide 70, which is mounted for reciprocal sliding movement on the upper wall of the housing 4, the slide being confined during such movement between guides or ribs 71, which are secured to such wall.

Reciprocal movement of the slide 70 is effected by means of a cam 73, hereinafter referred to as the seamer cam, and having a cam groove 74 in its lower face. The slide 70 has a bearing pin 75 mounted in one end thereof, which supports a cam roller 76, a needle bearing 77 being interposed between the pin and roller. The roller 76 rides in the cam groove 74, as the cam 73 is rotated.

The cam 73 is secured, as by screws 78, to the main gear 79 of the seamer, and the gear 79, in turn, has secured thereto, as by screws 80, a clutch operating cam 81, having a recess 82 in its upper edge. The gear 79 is secured, as by a key 83, to the upper end of a cam shaft 84, being retained against axial displacement from said shaft by a dog point set screw 85.

The gear 79 is adapted to be driven by a gear 86, which is loosely mounted on a clutch shaft 87, the latter being journaled in and supported by a bearing 87a. The clutch shaft has keyed to the lower end thereof a gear 88, hereinafter referred to as the head gear driver, and which is in driving engagement with the head gear 9 of the seamer. It may be noted at this point that the clutch shaft is in continuous rotation, so that the seaming head, acting as a flywheel, relieves the motor. The clutch, as hereinafter described, being operated only when a can is brought into position, also relieves the motor from constant work.

The clutch shaft 87 is provided adjacent its upper end with a clutch, preferably of the single multi-disc dry type, and consisting of a drive cup 89, which is keyed on the hub sleeve of gear 86, and a member 90, which is keyed to, but slideable longitudinally of the clutch shaft. The clutch member 90 is adapted to be moved when the clutch is to be energized, and for this purpose, the member 90 is engaged by the yoke of a lever 91, which is keyed to a rock shaft 94, extending

transversely of the seamer and to the top housing 7 thereof. The shaft 94 is suitably journaled in brackets or ears 95 depending from the upper wall of this housing. The lever 91 is provided at its opposite end with a cam roller 96 which is normally urged into engagement with the upper surface of the clutch operating cam 81, as by means of a coil spring 97 which is interposed between a laterally-disposed seat 98 on the lever and a set screw 99 secured to the upper wall of the top 7.

The shaft 94 projects beyond one of the side walls of the top 7 and has keyed thereto adjacent such projecting end a brake lever 100, to one end of which is secured a rod 101, whose lower end is pivotally secured to one end of a treadle 102, which is mounted to rock about a shaft 103 extending from the pedestal 1 adjacent the base portion 2 thereof.

A brake is also provided consisting of a pair of substantially semi-circular lined brake straps 104, which are pivotally connected at one end, as by a pin 105, and are normally urged into braking contact with the drive cup 89 of the clutch by means of a coil spring 106. The spring 106 is mounted on a rod 107, which extends through ears 108 on the straps 104, the spring being interposed between one of these ears and a washer 109 mounted near one end of the rod. The rod is secured against displacement from the ears 108 by means of a nut 110 secured to its other end. The spring thus acts to normally force the brake straps 104 against the drum portion of the drive cup 89 of the clutch.

For the purpose of releasing the brake at the time the seamer is placed in operation, a lever 111 is provided having a boss 112 which is mounted upon an eccentric bushing 113 (Fig. 7) which is secured to the base of the housing 7. This lever 111 has one arm 114 thereof pivotally connected to a pin 115, which pivotally joins a pair of links 116 and 117, which are connected to the ears 108 of the brake straps. The other arm 118 of the lever 111 has a swivel connection 45 with a rod 119, which is pivotally connected to an arm 120 which extends from the brake lever 100. When the rod 119 is moved to the left, as viewed in Fig. 4, the point of connection of the links 116 and 117 is moved downwardly, as viewed in Fig. 4, thereby releasing the brake, and at the same time, the clutch is energized. The eccentric bushing 113 serves to insure the straight line movement of the point of connection of the links 116 and 117.

Means are also provided for supporting the can to be double-seamed in a position to be acted upon by the seaming rolls, such means being actuated by the treadle 102. Such means are best shown in Figs. 8 and 9 and comprise a bracket 121 which is mounted on the pedestal 1. This bracket is provided with a tubular portion 121a having a bore 122a, in the end of which a sleeve 122 is mounted and maintained against rotation by a key 123. The sleeve 122 is provided 60 with a radially extending flange 123a which terminates in a flared skirt 124. The flange has secured thereto, as by screws 125, a base plate 126 of generally rectangular form, and to which, in turn, is secured a top 127, shown, in this instance, as a round top.

Extending through the sleeve 122 is a spindle 128 having a lock nut 129 secured to its upper end and bearing against a shoulder 130 of the sleeve. The spindle extends also through a sleeve 75 131, which extends into the lower end of the

bore 121, and is retained by a lock nut 132, which is in threaded engagement with the spindle. A coil spring 133 is disposed within the bore 121, being interposed between the sleeves 122 and 131.

The spindle 128 has secured to the lower end thereof a grooved collar 134, which is locked in position by a lock nut 135. This collar is engaged by the yoke 136 of a lever 137, which is pinned to a shaft 139 journalled in and extending transversely of the bracket 121. The shaft 138 has pinned to one end thereof a lever 139 having a forked end 140 in which a pin 141 is secured. The pin 141 has an aperture 142 therethrough which the upper end of a rod 143 extends, the rod being secured to the pin by a set screw 144.

The rod 143 is adjustably secured at its lower end to a sleeve 145 having a forked lower end 146, which is pivotally connected to the treadle 102 at a point at the opposite side of the shaft 103 from that to which the rod 101 is secured.

The lever 137 has revolutely mounted upon a stud 146a secured to its rear end, a cam roller 147.

The bracket 121 is provided with a tubular portion 148 having a bore 149 therein in which a cam member 150 is secured as by a collar 151, the cam member, although secured by said collar, being free to rotate within said tubular portion 148. The member 150 has a flange portion 152, the face 153 of which forms a cam surface adapted, at times, to engage the cam roller 147. The member 150 is keyed to the lower end of the cam shaft 84.

Mounted on the bracket 121 about the tubular portion 121a of the latter, is a circular disc-like member 154 having spaced concentric flanges 155 and 156 forming an annular trough into which the overflow from cans being seamed may enter. The flange 156 is provided at diametric points with horizontally extending flanges or ledges 157 and 158, the ledge 157 having mounted thereon an inlet can table 159 and the ledge 158 having mounted thereon an outlet can table 160. Secured to the table 159 adjacent its rear edge is a can guide 161, which may be adjusted forwardly or rearwardly, in accordance with the size or diameter of the can to be seamed.

In order to eliminate any tendency of the can, after being seamed, to stick to the lower surface of the chuck plate 41, means are provided for knocking the can, at the conclusion of the seaming operation, from said plate. Such means comprises a knockout rod 162, which extends through the axial bores 43, 44 and 46, and has a thrust collar 163 secured to its upper end, as by a cotter pin 164. The lower end of the knockout rod 162 is normally disposed substantially flush with the lower end of the bore 46, and is maintained in such position by means of a compression coil spring 165 which is interposed between the collar 163 and a seat 165a formed at the bottom of a recess 166 within the support 8.

The knockout means further includes a knockout screw 167, which is adjustably secured to the yoke 62, and is disposed so that its lower end is immediately above and in spaced relation to the upper end of the rod 162.

The seamer is adapted to be driven by a motor 168 which is mounted laterally of the top housing 1, and drives the clutch shaft 87 through the intermediary of a pulley and belt drive 169.

The aforesaid description is primarily that of a double seamer which has been set up to double seam round cans, and the following description

will accordingly be directed more specifically to the seaming of such cans, reference being had also to Figs. 10 to 20 inclusive, which are intended to diagrammatically illustrate the cycle of operations incident to the double seaming of a single can. In connection with such operation, the operations of the seamer, as a whole, will be described.

In commencing the operations, the operator will place the can body B, with a top T mounted thereon in a position to be connected to such body, on the table 159 and against the guide 161 thereof, it being understood that this table is in its lowermost position. He then pushes the can body along the guide 161 and onto the top 127 of the base plate 126, the can being approximately centered on this top.

Having thus located the can, the operator will depress the treadle 102, and thereby, through the intermediary of the sleeve 145, rod 143, lever 139, and spindle 128, elevate the can so as to bring the top T thereof into engagement with the chuck plate 47, thereby clamping the can between the top 127 and the plate 47. Incident to this operation, spring 133 is compressed to a certain degree, so that the clamping engagement is of a yielding character, permitting movement of the can in a direction transverse to its axis, so as to permit it to be centered on the top 127 in a manner to be presently described.

The depression of the treadle 102 also results in an elevation of the rod 101, thereby causing the brake to be released, and the clutch to be energized. This results in the various moving elements of the seamer being set into operation. More specifically, the main gear 79 will be rotated, the head gear driver 88 being already in rotation. As the seaming head 11 is rotated by the head gear driver 88, guide plates 92, which are secured to the inner ends of the seaming arms 21 (see Fig. 10), engage the can body, and serve to center the latter and to maintain it against displacement during the seaming operations. The rotation of the gear 79 causes simultaneous rotation of the cam 73 and the clutch operating cam 81. As the latter begins to rotate, the cam roller 96, which has been elevated from the recess 82 of the cam against the tension of the spring 97, comes into contact with the upper edge of the cam, and is maintained by said spring against such edge during a complete revolution of the cam, that is, until the roller is again moved into said recess by the spring. The seamer therefore remains in operation for one complete revolution of the cam 81.

This corresponds to a complete revolution of the cam 73, which revolution may be described as covering one complete cycle of operations of the seamer. During such revolution of the cam 73, the seaming rolls 25 will be caused to move in and out of the arms 21, in a manner which will be apparent from the timing diagram of Fig. 14. It may be stated that at this point one pair of diametrically opposite rollers 25 are used for the first seaming operation, while the other pair of diametrically opposite rollers are used for the second seaming operation. The first and second operation rollers, as shown in Figs. 15 and 16, respectively, have somewhat different profiles or contours. The movement of the second operation rollers relatively to the arms 21, moreover, is different from that of the first operation rollers, since it is necessary that the second operation rollers do not come into contact with the work to be seamed until the first operation rollers have

completed their work. This differential in movement is effected by using for the first operation rollers, linkage which is of somewhat different dimensions than the linkage for the second operation rollers, as hereinbefore referred to.

During the seaming operations which are about to be described, the can is automatically maintained in elevated position due to the action of the cam surface 153 upon rotation of the cam member 150, which surface engages the cam roller 147 during the substantial portion of the revolution of the cam shaft 84 and thereby maintains the lever 137 in can elevating position. This enables the operator to remove his foot from the treadle 102 immediately after the seamer is placed in operation.

Referring to Fig. 14, it will be noted that during the first 18° movement of the cam 73, the movement of the cam roller 76 in the groove 74 of said cam is such that the pair of first operation rolls 25 approach the flange F of the can top T, the position of such rolls at the beginning of this movement being indicated by the dotted lines in Fig. 17 and the position thereof at the conclusion of the movement being indicated by the solid lines.

As the cam 73 rotates another 96 degrees, the first operation rolls are moved further inwardly, producing a curling and bending of the flanges of the body and cover of the can, as shown in Fig. 18, the rolls being maintained in this position during another 27 degree movement of the cam 73, the maintenance of the rolls in such position being referred to in the diagrams as the "dwell".

In further explanation of the above movements, it may be stated that the movements of the rolls are effected by movement of the spider 48 downwardly, as viewed in Fig 6B of the drawings. This downward movement of the spider 48 first causes the bell-cranks 57 to move about their shafts 58 in such a direction as to cause downward movement of the forks 36, until the lines A—A connecting the axes of the pins 53' and pins 56 are disposed at right angles to the axis of the spider. This position of the parts constitutes the "dwell," the relationship between the spider 48, links 55a, bell-cranks 57, pins 53' and 56 and shafts 58 being, in effect, a toggle or knuckle-joint relation.

Continued downward movement of the spider 48 results in a reversal of the direction of rotation of the bell-cranks 57 about the shafts 58, causing the axes of the pins 56 to move toward the spider, elevating the forks 36 and withdrawing the first operation rolls from the work.

Prior to the point at which such continued downward movement of the spider 48 causes a reverse rotating of the bell cranks 57, the second operation or finishing rolls approach the work, and at the completion of the seaming work of the first operation rolls, shown in Fig. 18, the second operation rolls reach the position shown in dotted lines in this figure. This movement of the second operation rolls is effected by the linkage shown in Fig. 6A of the drawings.

During the next 21 degree movement of the cam 73, the second operation rolls complete the double seaming operation, as shown in Fig. 19, the first operation rolls having, in the meantime, been retracted to a slight extent, to the position shown in dotted lines in such figure.

During the next 51 degree movement of the cam 73, the second operation rolls remain in contact with the double seamed edge, this period being known as the "dwell" of the second operation

rolls. The first operation rolls, during this period, remain in their retracted position.

During the "dwell" of the second operation rolls, the relation between the axis of the pins 53 and 56 (Fig. 6A) is such that a straight line connecting these axes is at right angles to the axis of the spider.

During the next 27 degree movement of the cam 73, both the first and second operation rolls are retracted to the position shown in Fig. 20, so as to clear the seamed edge of the can. As the cam 73 completes a single revolution, the first and second operation rolls return to their initial position. The retraction of the second operation rolls is effected by the continued downward movement of the spider 48, which causes the bell cranks 57, as shown in Fig. 6A, to be rocked in a reverse direction, as already described in connection with Fig. 6B.

It may be mentioned at this point that the timing, as determined by the seaming cam 73, only varies as the flange length or the gauge of the metal varies in the cans to be seamed, with minor variations due to can sizes.

As soon as the first and second operation rolls have cleared the can seam, as described above, the cam 153 releases the roller 147, permitting the spring 133 to pull the spindle 128 downwardly, and carrying the top 127 downwardly to its initial or loading position. At the same time, the seamed can is stripped from the chuck plate 47, due to the action of the screw 161, which comes into engagement with the upper end of the rod 162 and momentarily forces the latter downwardly so as to cause it to project from the lower end of the bore 46, thereby stripping the can from said chuck plate.

The can which has thus been stripped from the chuck plate 47 follows the top 127 downwardly, and when such top has reached its lowermost position, the operator may push the can onto the outlet can table 160, whence it slides into a suitable receptacle.

The toggle or knuckle-joint relation which has been described, together with the lost-motion provision of the first-operation roll linkage, is of considerable importance in connection with the present invention, since they permit the elimination of three cams, one to operate the first-operation rolls, one to operate the finishing rolls, and a third for operating the knockout rod. In addition, a great mechanical advantage is obtained by the utilization of the aforesaid toggle or knuckle-joint arrangement for driving the seaming rolls against the work, the pressures attained by such rolls against the work being nearly equivalent to those prevailing in coining operations. In this connection, it will be noted that the entire stress of seaming is borne by the toggle joints, thereby protecting the cam 73 and the essential and critical driving parts from such stresses. It will be further noted that the toggles, being diametrically opposed to each other, effectively counteract each other in a desired manner.

For the purpose of double seaming larger cans, which may be square, rectangular, oblong or round, the double seamer which has been described is modified in the manner shown in Figs. 23, 24 and 25 of the drawings.

Referring to these figures, it will be noted that in order to cause the seaming arms 21' to follow the general contour of the can, during the seaming operations, such arms are so mounted in the arms 18' of the seaming head 11' as to be revolvable in a horizontal plane. This requires that

the hub portions 21' of the seaming arms be free to rotate in the arms 18', a condition which is attained by unscrewing the screw 20a, so as to provide a clearance c, as shown in Fig. 25, between the flange of this screw and the upper end of the arm 18'.

In order to cause the seaming arms 21' to follow the contour of the can, a cam 180 is secured to the pin 42', and a chuck 45' is secured, as by screws 181, to the lower face of this cam, this chuck having, of course, the contour of the rectangular can which is to be double seamed. The cam 180 has a cam groove 182 therein, which is of the same contour as the can to be double seamed, and the seaming arm 21' has mounted therein a pin 183, which carries a cam roller 184, which rides in the groove 182, thereby causing the seaming arm to follow the contour of the can to be seamed.

The mechanism for moving the seaming rolls 25' relatively to the seaming arms is essentially the same as that described in connection with the double seaming of small cans, but in this case, it will be noted that the linkage between the ears 52' of the spider 48' and the bell crank levers 57', is somewhat different, due to the larger dimensions of the larger cans. Such linkage comprises links 55' which are pivotally connected to the ears 52', to idler supporting levers 190, pivotally supported on the seaming head 11' as at 191 and to links 192. The links 192 are pivotally connected to the bell cranks 57'.

It is to be understood that while the seaming head shown in Fig. 6 has been described with reference to the seaming of round cans, and the head shown in Fig. 24 has been described more particularly with reference to the seaming of cans having a rectangular contour, that the head in Fig. 6 can be readily adapted for the seaming of cans other than round and the head in Fig. 24 can be easily adapted for the seaming of round cans.

In order to adapt the head of Fig. 6 for the seaming of cans other than round, it is only necessary to free the hub portions 20 of the seaming arms 21 by unscrewing the collars 20a, provide a cam similar to the cam 180 of Fig. 24, a chuck similar to the chuck 45' and a cam roller similar to the cam roller 184. In order to adapt the head of Fig. 24 for the seaming of round cans, it is only necessary to eliminate the contour cam 180 and cam roller 184 and lock the hub portions of the seaming arms 21' by means of the collars 20a.

If it be assumed that the heads in Figs. 6 and 24 have been set up to operate on round cans of sizes and flange widths well within the normal dimensional range of each head, a schedule of operational modifications may be set up in the following manner.

1. If it be desired to operate on a can of a round shape, but slightly larger, having the same width of seam flange, the only change to be made in either of the heads shown in Figs. 6 and 24 is to change the chuck size.

2. If it be desired to operate on a can of round shape of substantially the same size but with a wider seaming flange or stiffer blank metal, the only changes necessary in the seaming heads of Figs. 6 and 24 are to slightly modify the profile of the cam shown in Fig. 11 of the drawings and to adjust the screw 185 and slide 186 of each respective linkage to produce long periods of ironing contact between the forming rolls and work.

3. If the same operations as in (2) is desired

but for a can of larger size, an additional change of a chuck is required.

4. If it be desired to seam a square can of approximately the same size and same width of seaming flange, the seaming heads of Figs. 6 and 24 are changed by providing a contour cam similar to cam 180, loosening the screw 20a, connecting the seamer roll supporting arm to the contour cam through the medium of the roller 182 and pin 183, and providing a chuck of the contour of the can being seamed.

It may be noted that in each instance, the modification effected are identical, the fundamental distinction between the seaming head of Fig. 24 and Fig. 6 being one of dimension and not of kind.

Referring to Figs. 26 and 27, it will be seen that in order to permit an increased travel of the seaming rolls, as when seaming wide end flanges, provision is made for varying the pivotal point of connection of the links or levers 192 to the bell crank levers 57'. This is accomplished by means of screws 185, adjustment of which causes slides 186 to which the links 192 are pivoted to move upwardly or downwardly along the inner faces of the levers 57'. This adjustment is also adaptable for use with that form of construction shown in Fig. 6.

If desired, the main drive shaft of the machine may be utilized to drive the feed mechanism (not shown) for the can bodies and tops, the construction of the machine readily adapting such shaft for these functions.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:

1. In a machine of the character described, a revolvable seaming head having hollow arms, arms having hollow hub portions mounted in said first-named arms and having hollow portions extending transversely to said hub portions, lever pivotally mounted in said transverse arm portions, seaming rolls journaled in said levers, and means for transmitting a rocking movement to said levers, said means including bell crank levers having arms extending into said hub portions, forked elements mounted for reciprocal movement in said hub portions, stems slidably mounted in said forks, levers pivotally mounted on said second-named arms and movable by said stems, and links interconnecting said last-named levers with the levers in which said seaming rolls are journaled.

2. A machine of the character described, a revolvable seaming head; an arm having a tubular hub portion at one end thereof and being attached to said head at the hub portion; a seaming roll carrying mechanism mounted on said arm; and means for actuating said mechanism comprising, a bell crank lever pivotally mounted on said arm adjacent to the hub portion thereof, a second bell crank lever pivotally mounted on said head and having an arm thereof extending into alignment with the opening through said hub portion, an operative connection between said arm of said second bell crank lever and the first mentioned bell crank lever comprising a compression spring located within said hub, whereby movement of said second bell crank is transmitted to the first mentioned bell crank.

13

through said spring and means for rocking said second bell crank lever.

EDWARD V. CRANE.
KARL KUHN.
